UNITED STATES PATENT OFFICE.

WILLIAM SEATON, JR., OF NEW YORK, N. Y.; JEANNETTE NEILSON SEATON ADMINISTRATRIX OF SAID WILLIAM SEATON, JR., DECEASED.

MECHANICAL STOKER.

1,048,356.

Specification of Letters Patent. Patented Dec. 24, 1912.

Application filed June 27, 1905. Serial No. 267,174.

To all whom it may concern:

Be it known that I, WILLIAM SEATON, Jr., a citizen of the United States, and a resident of the borough of Richmond, city of New York, State of New York, have invented a certain new and useful Mechanical Stoker, of which the following is a specification.

My invention relates to a new form of mechanical stoker whereby I am enabled to produce combustion by a simple means which is more effective than any apparatus for a similar purpose which has hitherto been in use.

In order to produce complete combustion it is necessary to feed the fuel into the furnace in a regular manner, to regulate the thickness of the fuel on the grate, to partially coke the fuel on the grate, to regulate the speed at which the fuel advances on the grate, to regulate the admission of air to the fire above and below the grate and to regulate the frequency of agitation of the fire. All of these objects are successfully accomplished by the means herein disclosed and in addition provision is made for the regular emission and disposal of ashes so that they do not accumulate under and burn out the grates, and for the frequent inspection of the condition of the fire. Provision is also made for banking the fire and for preventing it from eating back into the magazine.

Other advantages will appear in connection with the description of the preferred form of apparatus and the mode of operation thereof.

In the following I have described with reference to the accompanying drawings one form of structure illustrating my invention, the features thereof being more particularly pointed out hereinafter in the claims.

In the drawings Figure 1 is a side elevation partly diagrammatic and partly in section along the line 1--1 of Fig. 2 of a furnace and boiler provided with the preferred form of my new mechanical stoker. Fig. 2 is a front elevation of the same, parts being removed to more clearly illustrate the construction of the apparatus. Fig. 3 is a side elevation, parts being broken away, of a portion of the apparatus illustrated in Fig. 1 on a slightly enlarged scale, but showing the magazine hopper closed and the apparatus arranged for the ready inspection of the interior of the furnace. Fig. 4 is a de-

tail plan view of a portion of the grate bars and the supporting beams. Fig. 5 is a detail view of the front end of the grate bars, parts being broken away to more clearly illustrate the means for removing the grate bars from the grate. Fig. 6 is a diagrammatic view of the actuating mechanism on a slightly enlarged scale, parts being broken away, the operating cylinder being displaced from its true position (Fig. 1) for convenience of illustration. Figs. 7 and 8 are detail views on an enlarged scale illustrating one means of supporting one end of the grate bars. Fig. 9 is a detail view, parts being broken away, to more clearly illustrate the control of the actuating mechanism.

Similar numerals of reference indicate similar parts throughout the several views.

1 represents the ordinary form of fire tube boiler provided with tubes 2, 2 through which the products of combustion pass into the flue 3. The boiler is supported in any convenient manner.

4 is the combustion chamber and 5 is the furnace provided with an arch 6 of fire brick in the usual manner.

7, 7 and 8, 8 represent the grate bars separate from each other and separately supported on bearing beams 9 and 10. The alternate bars 7, 7 are hooked over beam 10 and bars 8, 8 over beam 9. The free ends of the bars are lengthened to permit the reciprocating motion hereinafter described. Beam 10 is supported on wedges 11, one at each end, resting on brackets 12 secured to the side wall of the furnace. The brackets 12 are provided with upwardly extending lugs or guides 13 to prevent lateral movement of the beam 10.

The beam 9 is preferably made integral with the back plate 14 of a rocker pivotally supported at 15 in a base plate 16. The rocker also comprises a front plate 17 having a lip 18 preferably curved on a radius 100 having point 15 as its center. The rocker is provided with a rib 19 for the purpose hereinafter set forth. Back plate 14 is provided with openings 20 to permit the ends of grate bars 7, 7 to project therethrough during the oscillation of the rocker and to provide for ready removal of the bars from the furnace, the relationship between the bars and the openings being such that no air passes therethrough. The back plate 14 also

22 carries doors 21 to permit of access to the ash pit 22.

A magazine hopper 23 is supported in front of the furnace in any suitable manner, such as by means of standards 24 and is adapted to discharge into the furnace at 25. The front of hopper 23 is formed by a gate 26 pivoted in the walls of the hopper on pivots 27. This gate is adapted to swing 10 so as to close the bottom of the hopper as and when desired as hereinafter set forth. Between the back wall of hopper 23 and the front of the furnace is an air chamber 28 provided with a series of apertures 29 for admitting air, and a series of apertures 30 for discharging the same into the front part of the furnace.

There is a gap 31 between the top of the inner ends of the grate bars and the bridge wall 32. The size of this gap can be adjusted by means of the wedges 11 so as to increase or decrease the same as desired thus providing means for the emission of ashes without admitting air from below 25 around the ends of the grate bars.

The ash pit 22 is shaped so as to provide for a water seal 33 which in conjunction with a plate 34 secured to beam 10 is adapted to form additional or independent means 20 for preventing the air from passing from the ash pit up through the gap 31. The water in the water seal also serves to quench the fire in the ashes which latter are adapted to be removed from the ash pit by means 30 of a conveyer comprising an endless chain or wire 35 carrying disks, flights or buckets 36, and driven by any suitable power.

The apparatus for actuating the rocker and connected parts comprises a cylinder 37 adapted to oscillate on pivot 38 on a suitable bed plate 39. The rocker is pivoted on the end of piston rod 40 as at 41 to rib 19 so that the reciprocating motion of the piston rod is communicated to the rocker which oscillates about point 15. The piston 42 of cylinder 37 may be driven by any suitable means, but as illustrated, is adapted to be driven by hydraulic pressure caused by pump 43. The water from pump 43 passes 45 through pipe 44 to a valve 45 in valve seat 46. Valve 45 is provided with passages 47 and 48. Passage 47 is adapted to register alternately with pipe 44 leading from the pump and pipe 49 leading to the cylinder 37, and pipe 49, then acting as an exhaust, and pipe 50 leading to the exhaust valve 51. Passage 48 is adapted to register alternately in a similar manner with pipe 44 and pipe 52 leading to the other end of cylinder 37, 55 and pipe 52, acting as an exhaust, and pipe 53 leading to exhaust valve 51. Valve stem 54 of valve 45 carries loosely mounted thereon an arm 56 having a weight 57 at its outer end. A segment 57^a having flanges 58 and 59 is fixed on valve stem 54 for the purpose

hereinafter set forth. An arm 60 loosely mounted in guides 61, suitably supported, is pivoted to the rocker as at 62, and is provided with adjustable nuts 63 and 64 adapted to contact alternately with arm 56 as the rocker oscillates. A bridge plate 65 is hooked to front plate 17 of the rocker, the outer end sliding on the grate bars and is adapted to bridge between said plate 17 and the grate bars. The front end of arch 6 70 75 is supported on a rib 66 preferably integral with the back wall of the hopper.

The operation of the apparatus is as follows: The fire being started the hopper 23 is filled with coal which rests upon the front 80 plate 17 of the rocker the parts being arranged as shown in Fig. 1. The piston rod 40 is then caused to reciprocate by the means disclosed thus causing the coal to advance upon the front plate 17 and the bridge 85 plate 65 to the grate bars along which it is moved by the reciprocating motion imparted to the alternate bars by the rocker. This advancing motion of the coal is made in such manner that no holes are formed in the fire 90 as the coal is constantly being crowded upon plate 17. The movement of valve 45 is controlled by the movement of arm 56, in turn actuated by rod 60, the nuts 63 and 64 being adjustable toward and away from 95 each other to provide for a quicker or slower reciprocation of piston rod 40. When arm 56 is pushed past the vertical position in either direction, weight 57 causes arm 56 to fall against flanges 58 or 59 of segment 100 57^a fast on valve stem 54, hence turning the valve to cause piston rod 40 to descend or advance as the case may be. The oscillation of plate 17, to which rod 60 is pivoted, causes rod 60 to reciprocate and to bring 105 nuts 63 and 64 alternately into contact with arm 56. As the coal advances along plate 17 and bridge plate 65 the heat reflected from the arch 6 partially cokes the coal on the plates. This partially coked coal is 110 burned on the grate bars as it advances, and the ashes are carried over the ends of the bars and deposited in the ash pit 23 by gravity, the water in the ash pit serving to quench the fire in the ashes and preventing 115 the grate bars from being warped by an accumulation of hot ashes underneath them. The gases that arise from the partially coked coal on plate 17 and bridge plate 65 may be mixed with a regulated supply of air 120 admitted through apertures 30 and burned over the incandescent fuel in such manner that the whole operation is practically smokeless.

The stroke at the point of emission of the 125 coal from the hopper is greater than any where else, the radius from pivot 15 to lip 18 being greater than the radius from said pivot to beam 9 hence the coal nearest the point of admission has the tendency to travel 130

fastest which results in closing up the holes in the fuel bed due to coking on the plate, or to an unequal rate of combustion on the bars.

5 The thickness of the fuel bed may be regulated by adjusting the stroke of the piston, a long stroke permitting more coal to be emitted from the hopper than a short stroke. If a short stroke is preferred the thickness 10 of the fuel bed may be regulated by determining the point in the cylinder about which the piston shall make its stroke because if the rocker is oscillated about a point which more or less shuts the bottom of the 15 hopper the thickness of the fuel bed is varied although the length of the stroke may remain the same. The angle of plate 17 and bridge plate 65 is just below the angle of repose of the coal hence the coal will not slide 20 on the plates, but must be pushed by other coal coming in from behind. The coal will not move forward unless coal is coming from the hopper, the advancing motion being caused by the combined rocker motion and 25 pushing effect of the coal falling from the hopper behind the coal on the plates. The oscillation of the rocker causes the grate bars 8, hooked onto the beam 9, to move horizontally with a slightly vertical motion, the 30 amount of vertical motion being controlled principally by the width of the beam, the wider the beam the more vertical motion. Provision may be made against the sifting of the fine particles of coal which may have 35 escaped being coked by making the openings between the grate bars smaller at the front than at the rear end. The combined effect of this motion of the grate bars is to cause a sliding, shaking and rasping motion which 40 is beneficial by breaking up the fuel bed and clinkers and removing the ashes from the under side of the fire. The forward horizontal movement of the bars carries the coal with them but the coal is prevented 45 from following the grate bars in their backward movement by a new charge of coal falling from the hopper onto plates 17 and 65 behind the coal carried forward as described thus crowding the fuel together and 50 preventing exposure of the grate bars from the reflected heat from the arches.

The ashes which have not been sifted through the grate bars as described and the clinkers are carried to the inner end of the 55 bars where they are macerated and pushed off into the water in the ash pit. The plate depending in the water seal cuts off the air from passing through the gap 31 and thus prevents poor combustion, the air being 60 forced to pass through the fuel bed and not permitted to pass around it. The ashes which sift through the grate bars into the water in front of the plate 34, together with the ashes pushed over the ends of the grate 65 bars, are conveyed out by the conveyer which

is adapted to travel up out of the seal at either end, dragging the ashes with it but leaving the water behind.

It is obvious that details of construction and the arrangement of parts may be considerably varied without departing from the spirit of my invention and I do not restrict myself to the details as shown and described or to the arrangement of parts illustrated but

What I claim and desire to secure by Letters Patent of the United States is:—

1. In an apparatus of the character described the combination of grate bars, a rocking member adapted to support one end of said grate bars and to rock the same, a feeding and coking plate integral with said rocking member and inclined toward the grate bars in its normal position and means for imparting movement to said rocking member, the arrangement of parts being such that the fuel falling upon said plate is caused to travel along said grate bars.

2. In an apparatus of the character described the combination of grate bars, a support for one end of said grate bars adapted to impart movement to said grate bars, a feeding and coking plate integral with said support and inclined toward the grate bars in its normal position and means for imparting movement to said support, the arrangement of parts being such that fuel falling upon said plate is caused to travel along said grate bars.

3. In an apparatus of the character described the combination of grate bars, a movable support for one end of said grate bars, a stationary support for the other end, a feeding and coking plate integral with said support and inclined toward the grate bars in its normal position and means for imparting movement to said movable support whereby horizontal movement is given to some of said grate bars with relation to the others, the arrangement of parts being such that fuel falling upon said plate is caused to travel along said grate bars.

4. In an apparatus of the character described the combination of grate bars, a support for one end of said grate bars adapted to impart movement to said grate bars, a feeding and coking plate integral with said support and inclined toward the grate bars in its normal position, means for imparting movement to said support and a 105 hopper adapted to discharge on said plate, one side of said hopper forming means for closing said hopper.

5. In an apparatus of the character described the combination of grate bars, a support for one end of said grate bars adapted to impart movement to said grate bars, a movable feeding and coking plate integral with said support and inclined toward the grate bars in its normal position, means for 125 130 135 140 145 150 155 160 165 170 175 180 185 190 195 200 205 210 215 220 225 230 235 240 245 250 10005 10010 10015 10020 10025 10030 10035 10040 10045 10050 10055 10060 10065 10070 10075 10080 10085 10090 10095 10100 10105 10110 10115 10120

imparting movement to said support and means for regulating the degree of said movement.

6. In an apparatus of the character described the combination of grate bars, a support for one end thereof adapted to impart movement thereto, a feeding and coking plate integral with said support and inclined toward the grate bars in its normal position, means for imparting movement to said support and means for controlling the degree of said movement.

7. In an apparatus of the character described the combination of grate bars, means for adjustably supporting one end of said grate bars, a rocking member adapted to support the other end of said grate bars and to rock the same, a hopper, a feeding and coking plate integral with said rocking member and inclined toward the grate bars in its normal position, said plate being adapted to receive fuel from said hopper, and means for imparting movement to said rocking member, the arrangement of parts being such that fuel falling upon the plate is caused to travel along the grate bars.

8. In an apparatus of the character described the combination of grate bars, means for adjustably supporting the same at one end, a rocking member adapted to support the same at the other end and to rock the same, a feeding and coking plate moving with said rocking member, means for imparting movement to said rocking member and means controlled by said rocking member adapted to limit the degree of said movement.

9. In an apparatus of the character described the combination of grate bars, a rocking member adapted to support one end of the same and to rock said grate bars, a feeding and coking plate integral with said rocking member and inclined toward the grate bars in its normal position and a hopper adapted to discharge on to said plate,

the arrangement of parts being such that the movement of the bars and the plate together with the pressure of the coal from the hopper will cause the coal to travel along said grate bars.

10. In an apparatus of the character described the combination of grate bars, a beam at one end of said grate bars upon which some of the grate bars rest and over which others are hooked, a rocking member at the other end of said grate bars upon which the grate bars hooked on the beam rest and the grate bars resting on the beam are hooked, means for actuating said rocking member so as to communicate combined horizontal and vertical movement to said grate bars, the vertical movement being imparted at only one end of said grate bars, a feeding and coking plate moving with said rocking member, a plate bridging between said first named plate and said grate bars and a hopper adapted to discharge upon said first named plate, the parts being so arranged and connected that the fuel discharging from the hopper will be caused to travel along said first named plate and the grate bars.

11. In an apparatus of the character described the combination of grate bars, a rocking member supporting one end of the same and adapted to rock the same, a feeding and coking plate integral with said rocking member and inclined toward the grate bars in its normal position, a hopper adapted to discharge upon said plate and means permitting air to be admitted into the front part of the furnace above said plate.

In witness whereof I have hereunto signed my name in the presence of two subscribing witnesses.

WILLIAM SEATON, Jr.
